C. H. MARTIN

STOCK HOLDER FOR PRINTING PRESSES

Filed May 8, 1923

UNITED STATES PATENT OFFICE.

CHARLES HUGH MARTIN, OF LOS ANGELES, CALIFORNIA, ASSIGNOR OF ONE-HALF
TO ARTHUR F. LARRABEE, OF LOS ANGELES, CALIFORNIA.

STOCK HOLDER FOR PRINTING PRESSES.

Application filed May 8, 1923. Serial No. 637,419.

To all whom it may concern:

Be it known that I, CHARLES HUGH MARTIN, a citizen of the United States, residing at Los Angeles, in the county of Los Angeles and State of California, have invented a new and useful Stock Holder for Printing Presses, of which the following is a specification:

This invention relates to means adapted to hold stacks of envelopes, cards, and small sheets against the barrier of a printing press, to which such thin flat objects are fed by a pneumatic feeder.

Heretofore the stock holders for such thin flat objects have been secured to the printing press table and are arranged to apply a slight edgewise pressure on the objects to hold them toward the barrier, and it has been necessary to release and move the same away from the barrier in order to permit a fresh supply of stock to be placed in position to be picked up by the pneumatic sucker; and after the supply of stock has been replenished, the stock holder has to be re-turned toward the barrier and again secured to the table so as to hold the stock in position against such barrier; as a result, the tension applied by the stock holder to the successive stacks of stock is variable; and the feeding of sheets is irregular.

An object of this invention is to provide a stock holder which can be easily adjusted to hold the predetermined stock and can be easily shifted to allow the stock to be replenished, and which can be invariably returned to the exact adjustment, so that the same degree of pressure upon the stock will be maintained throughout the printing of the stock to which it is set.

Another object is to provide novel means to retain the next lower sheets as the topmost sheet is lifted from the stack by the usual pneumatic sucker.

Another object is to so construct a stock holder that the supply of stock on a printing press stock table may be replenished with greater facility and ease than heretofore.

Another object is to so construct a stock holder, that small stock such as business cards may be printed upon a standard Miller press.

The invention may be variously constructed and comprises a simple construction and

also additions to such simple construction whereby certain conditions are met and services are performed which in a majority of cases may not be met or taken care of:

This invention is applicable for use with what is known as the Miller automatic platen press feeder. Such feeders are provided with laterally adjustable side posts to prevent the stock from being displaced laterally; and such posts are positioned a short distance, about two and one-half inches more or less from the barrier; and it is not practicable to bring such posts close enough together to hold small cards or sheets, say four or five or less inches in length; and an object is to so construct the stock holder that it can not only be used alone for the smaller cards or sheets, but can also be used in conjunction with the stock holding posts of the Miller feeder when the cards or sheets are of a length to which the Miller feeder is adapted.

An object of the invention is to provide a pneumatic platen press feeder with adjustable stock positioning posts that can be adjusted to any desired position relative to the barrier, and that will afford a support for one end and the rear edge of the stack of stock; and to make provision whereby the stock can be supported at either or at both of its rear corners, and any part or all of such support can be instantly moved out of the way and again returned to the set position without any danger of being out of adjustment when returned.

Other objects, advantages and features of invention may appear from the accompanying drawing, the subjoined detail description and the appended claims.

The accompanying drawing illustrates the invention in some of the forms I at present deem preferable.

Figure 1 is a perspective view of a stock holder embodying this invention in use to hold small cards; a fragment of the printing press stock table and barrier therefor are shown.

Fig. 2 is a plan view of the device shown in Fig. 1. Dotted lines indicate an adjusted position of the auxiliary holding means, and dot and dash lines indicate an extended position of the stock holding arms.

Fig. 3 is a fragmental elevation from the right of Figs. 1 and 2 with the stock hold-

ing arms in the extended position indicated in dot and dash lines in Fig. 2, one of the stock retaining posts being partly in section.

Fig. 4 is an elevation partly in section on a plane indicated by line x^4 , Fig. 2, and showing another form of the stock retaining arms.

Fig. 5 is a plan view of a device embodying the features of the invention as applied in simple form to a printing press, a fragment of which is shown; dot and dash lines indicate a position of the stock holder arms extended.

Fig. 6 is a fragmental plan view showing in detail the pivoted end of the auxiliary holding means detached from the stock engaging means.

Fig. 7 is a section on line x^7 , Fig. 6.

1 indicates any suitable standard printing press stock table having a barrier 2 at one side thereof and being provided with the usual bevel slot 3 in which the support 4 of the stock holder 5 is slidably mounted.

The stock holder 5 comprises a transverse member 6 fixed to the sliding support 4, and horizontally swinging arms 7 having at their free ends upwardly extending roughened posts 8, and pivotally connected to the transverse member as at 9 by any suitable means such as vertical rivets 10.

The posts 8 are shown as being transversely ridged and are secured to the free ends of the arms 7 and are adapted to be swung horizontally into position to hold the stock, such as envelopes, or sheets, not shown, or the cards 11, against the barrier 2 and to afford sufficient resistance to uplift of the paper to prevent the second sheet from being sucked up by the first sheet when the first sheet is lifted directly by the sucker of the pneumatic feeder, not shown.

In Fig. 5, 12 indicates the usual adjustable stock posts or guides with which printing presses are commonly equipped to properly position the stock longitudinally on the table.

The horizontally swinging stock engaging means are held in and out of stock-engaging position by means of a helical spring 50 13 connected at its ends to the arms 7 by spring attachment eccentric pins 14 that are fixed to the arms and movable in recesses 14' formed at the ends of the transverse member 6, from one to the other of stops 15 and 16. The stops 15 serve to stop the arms 7 when the stock engaging means are in position to hold the stock against the barrier 2, and the stops 16 serve to hold the upright ridged or roughened posts 8 out of engagement with and out of the way of the stock. It is thus seen that the pins 14 and stops 15 form stop means to position the arms 7 in stock engaging position, that is when the arms 7 are in stock engaging position on the posts 8 will engage the stock.

When either or both of the arms 7 are swung away from stock engaging position the tension of spring 13 is increased, and after either pin passes the dead center in either direction, the spring swings the pin along the recess until the pin rests on a stop. Said dead centers are aligned with the pivots 10 so that the spring 13 will operate either arm or both of the arms to continue the opening or closing operation as the case may be, until either or both the arms 7 and ridged or roughened posts 8 attain either the position shown in solid lines or the position indicated by dot and dash lines in Figs. 2 and 5. In said dot and dash position the arms 7 are approximately parallel with the barrier 2 and are practically aligned with the transverse member 6; and the supply of stock may then be replenished without interfering with the stock engaging means.

The stops 16 on the transverse member 6 position the arms in extreme extended or retracted position. After the supply of stock has been replenished the stock engaging means may be returned to stock-engaging position where it will without adjustment engage the stock with the same pressure as before.

To adapt the device to business cards or other stock of such small dimensions that the usual stock guides 12 cannot be adjusted close enough together to engage such stock, I provide auxiliary stock engaging or positioning means comprising arms 17 and posts 18. The arms 17 are detachably and pivotally connected to the arms 7 by means of screws 19 threaded into the threaded apertures 20 in the arms 7. The screws 19 are tightened so that the arms 17 frictionally engage the arms 7, thus being held in adjusted position. The arms 17 respectively conform at their free ends to the periphery of the bases of the posts and are bent downward as at 21 to bring the under faces of the outer ends of the arms 17 flat upon the table so that a single sheet will be held and positioned as well as any top sheet in a stack of sheets.

In order to facilitate attaching, adjusting, and detaching, the auxiliary stock positioning means relative to the arms 7, I provide the arms 17 with slots 17' that open at the inner or adjacent edges of the arms 17 and that are adapted to accommodate the bodies of the screws 19; and the closed ends of the slots are countersunk as at 17'' so that when the arms 17 are applied to the arms 7 with the screws 19 at the ends of the slots, and tightened, the heads of the screws 19 will serve to fix the arms 17 in mounted and adjusted position on the arms 7 and the arms 17 may be attached to, or detached from, the arms 7 by loosening without removing the screws 19.

In Fig. 4 I have shown a post analogous to the post 8, but comprising a smooth body having a fine helical spring 8' therearound; the inside diameter of such spring being 5 slightly smaller than the outside diameter of the post 8, so that the coil will be held on the post 8 by friction and will afford a corrugated or roughened surface for the post. I find that the form shown in Fig. 10 4 is adapted for use on all kinds of stock; but is especially adapted for holding soft stock such as blotters. The rounded edges of the spring prevents "chewing" the edges of the soft stock by the unyielding ridges 15 of the ridged posts.

In practice the size of the stock to be printed is predetermined; and assuming that the stock is of such length that the end guides 12 may be used, such guides are 20 positioned to center the work, and then the stock holder 5 is so adjusted in the slot 3, relative to the barrier 2, that the correct pressure is applied to the stock contacting therewith. The stock holder 5 is maintained in such position by means of the screw 22 operating through a hole in the offset 22' of the transverse member 6 and in one of the threaded apertures 23 in the support 4, and tightening the screw in the aperture 30 fixes the support in the slot 3.

After the initial supply of stock has been exhausted, the stock engaging means may be moved outwardly by a slight movement as by a flip of the operator's fingers between the 35 posts 8, and the pins 14, on which the spring 13 operates, is thereby moved past alinement with the pivots 10; after which the spring 13 operates to retract the arms 7 and upright posts 8 to the position indicated by dot and dash lines, Fig. 2.

A new supply of stock may then be put in place without interference of the posts 8 which are then returned so as to extend 45 from the transverse member 6 toward the barrier 2 to stock-engaging position. Upon return of the stock engaging means, each of the posts 8 will engage the stock edges with a pressure corresponding to that with which it engaged the preceding supply.

50 The threads or ridges on the posts 8 contact with the rear edge of the stock as it is lifted upward by the usual pneumatic sucker, not shown, and effectively separates the indirectly lifted sheet or sheets of stock 55 from the directly lifted sheet and thus insures that only the one sheet carried by the pneumatic sucker will be lifted from the supply of stock.

When the stock is of such dimensions that 60 the stock guides 12 cannot be brought close enough together to operate effectively, the auxiliary stock engaging means is secured to the arm 7 by the screws 19; and the arms 18 are positioned to engage the lateral edges 65 of the stock to properly position or center

the same. The operation for replenishing the supply of stock is the same as described above.

It is thus seen that the spring affords yielding means cooperating with the pins, 70 cams and stops, to hold the pivotally mounted arms in and out of stock engaging position and it is understood that the invention is not limited to any specific construction and that it may be carried out in whole or 75 in part by means equivalent to those shown, without departing from the spirit of my invention.

The screw 22 is offset a distance from the longitudinal center line of the transverse 80 member 6 so that when the stock holder 5 is in retracted position the spring 13 will not extend over or so closely approach the screw 22 as to interfere with adjustment of said screw to change the position of the 85 stock holder relative to the barrier.

I claim:

1. A stock holder comprising a member adapted to be secured to a printing press stock table; and horizontally swinging stock 90 engaging means pivotally connected to said member.

2. A stock holder comprising a member adapted to be secured to a printing press stock table; horizontally swinging stock 95 engaging means pivotally connected to said member; and resilient means to hold said stock engaging means in stock engaging position.

3. A stock holder comprising a member 100 adapted to be secured to a printing press stock table; stock engaging means pivotally connected to said member and adapted to engage one of the edges of stock to be printed; resilient means to hold said stock engaging 105 means in stock engaging position; and auxiliary stock engaging means pivotally connected to said first mentioned stock engaging means and adapted to engage the lateral edges of said stock. 110

4. A stock holder comprising a member adapted to be secured to a printing press stock table; horizontally swinging stock 115 engaging means pivotally connected to said member and adapted to engage one of the edges of stock to be printed; resilient means to hold said stock engaging means in stock engaging position; and stops on said member to position said stock engaging means to engage said stock. 120

5. The combination with a printing press stock table and barrier therefor; of a stock holder comprising a member secured to said table; arms pivotally connected to said member and normally extending toward said 125 barrier; posts secured to the free ends of said arms and adapted to hold stock against said barrier with a predetermined pressure; said arms being adapted to be moved away from said barrier to permit replenishing the 130

supply of stock; and stops adapted to position said posts to engage the stock whereby said posts are caused to hold stock against the barrier with the same predetermined pressure.

6. A stock holder comprising a member adapted to be secured to a printing press stock table; arms pivotally connected to said member; posts fixed to the free ends 10 of said member; pins fixed to said arms near the pivotal connection of said arms; resilient means connected to said pins; and stops on said member with which said pins are adapted to engage to position said posts 15 to engage the stock.

7. A stock holder comprising a member adapted to be secured to a printing press stock table; arms pivotally connected to said member; ridged or roughened posts fixed 20 to the free ends of said member; pins fixed to said arms near the pivotal connection of said arms; resilient means connected to said pins; and stops on said member with which said pins are adapted to engage to position 25 said posts to engage the stock.

8. A stock holder comprising a member adapted to be secured to a printing press stock table; arms pivotally connected to said member; posts fixed to the free ends 30 of said member; coil springs encircling said posts; pins fixed to said arms near the pivotal connection of said arms; resilient means connected to said pins; and stops on said member with which said pins are adapted 35 to engage, to position said posts to engage the stock.

9. A stock holder comprising a member adapted to be secured to a printing press stock table; stock engaging means pivotally 40 connected to said member and adapted to engage one of the edges of stock to be printed; and auxiliary stock engaging means pivotally connected to said stock engaging means and adapted to engage the ends of 45 said stock.

10. A stock holder comprising a member adapted to be secured to a printing press; stock engaging means comprising arms pivotally connected to said member; posts 50 fixed to the free ends of said arms; and auxiliary stock engaging means comprising arms pivotally connected to said first mentioned arms, and posts fixed to the arms of said auxiliary stock engaging means.

11. A stock holder comprising a member adapted to be secured to a printing press stock table; stock engaging means comprising arms pivotally connected to said member; corrugated posts fixed to the free ends 60 of said arms; and auxiliary stock engaging means comprising arms pivotally connected to said first mentioned arms, and posts fixed to the arms of said auxiliary stock engaging means.

12. A stock holder comprising a member

adapted to be secured to a printing press; stock engaging means comprising arms pivotally connected to said member; posts fixed to the free ends of said arms; springs encircling and frictionally engaging said 70 posts; auxiliary stock engaging means comprising arms pivotally connected to said first mentioned arms, and posts fixed to the arms of said auxiliary stock engaging means.

13. In a stock holder comprising a barrier 75 adapted for use with a pneumatic feeder, pivoted arms provided with means to engage edges of stock to hold the stock against the barrier, resilient means to yieldingly hold the arms in stock engaging position; and means to adjust the arms toward and from the barrier.

14. In a stock holder comprising a barrier; a pivotally mounted arm adapted to be swung into and out of position to hold stock against the barrier; a pin on the arm; stops for the pin; and a spring adapted to cooperate with the pin to swing the pin from one side of the dead center to the stop on the side of the dead center on which the pin may be, so that the arm may be adjusted to predetermined position.

15. In a stock holder comprising a barrier; pivotally mounted arms adapted to be swung into and out of position to hold stock against the barrier; pins on the arms; a pair of stops for each of the pins; there being recesses between the stops of each pair through which said pins are movable, and a spring connecting the arms and adapted to cooperate with the pins to swing either or both the pins from either side of the dead center to the stop on the side of the dead center on which the pin may be, so that either or both of the arms may be adjusted to predetermined position.

16. The combination with a table and a barrier, of a member having two recesses and a pair of stops for each recess, said recesses having dead centers respectively between the stops; arms pivotally mounted on the table by pivots alined with the dead centers of the recesses; pins on the arms to engage the stops and movable in said recesses; and a spring connecting the arms and adapted to be swung past the dead center of one or both of the recesses, as one or both of the arms, as the case may be, is swung on its pivot.

17. In combination with a table and a barrier, two pivotally mounted arms adjustable toward and from the barrier and adapted to engage a stack of stock to hold it against the barrier, yielding means to hold the arms positioned to hold the stock in barrier engaging position; and means to cooperate with said yielding means to hold the arms out of stock engaging position.

18. The combination with a printing press stock table and a barrier therefor; of a 130

stock holder comprising a member adjustably secured to said table; arms connected to said member and normally extending toward said barrier, one of said arms being 5 pivotally connected to said member and adapted to be moved horizontally away from said barrier to permit replenishing the supply of stock; posts extending upwardly from the free ends of said arms and adapted 10 to hold stock against said barrier with a predetermined pressure; stop means to position said pivotally mounted arms in stock engaging position; and resilient means connected to said pivotally mounted arm to 15 normally hold said pivoted arm in stock engaging position.

19. The combination with a printing press stock table and a barrier therefor; of a stock holder comprising a member adjustably secured to said table; arms connected to said member and normally extending toward said barrier, one of said arms being pivotally 20

connected to said member and adapted to be moved away from said barrier to permit replenishing the supply of stock; posts extending upwardly from the free ends of 25 said arms and adapted to engage one of the edges of stock to be printed and hold said stock against said barrier with a predetermined pressure; stop means to position 30 said pivotally mounted arm in stock engaging position; resilient means connected to said pivotally mounted arm to normally hold said pivoted arm in stock engaging position; and auxiliary stock engaging means 35 adjustably connected to said arms and adapted to engage the ends of said stock.

In testimony whereof, I have hereunto set my hand at Los Angeles, California, this 28th day of November, 1922.

CHARLES HUGH MARTIN.

Witness:

JAMES R. TOWNSEND.
